UNITED STATES PATENT OFFICE.

HENRY BUREMANN, OF DAVENPORT, IOWA.

SAFETY APPLIANCE FOR ELEVATORS.

1,134,182.

Specification of Letters Patent.

Patented Apr. 6, 1915.

Application filed September 22, 1913. Serial No. 791,076.

To all whom it may concern:

Be it known that I, HENRY BURRMANN, a citizen of the United States of America, and resident of Davenport, Scott county, Iowa, have invented a certain new and useful Improvement in Safety Appliances for Elevators, of which the following is a specification.

My invention relates to safety appliances for passenger or freight elevators and has for its object to provide a means to automatically stop the cage or car from falling due to accidental breakage of the lifting mechanism.

Another object is to utilize the weight of the car to securely suspend it at any point in the elevator shaft where failure of the lifting mechanism might occur, and the providing of means, accessible from the interior of the car, for releasing it from such suspended position.

These and other objects which may hereinafter appear I attain by the mechanism illustrated in the accompanying drawings in which—

Figure 1 is a front elevation of the lower portion of an elevator car with my improved mechanism suspended from the floor thereof. Fig. 2 is a sectional view taken on line A B of Fig. 1. Fig. 3 is a sectional view taken on line D C of Fig. 1. Fig. 4 is a vertical cross section taken on line E F of Fig. 1. Fig. 5 is a side elevation of a portion of the device taken on line G H of Fig. 1. Fig. 6 is a horizontal cross section taken on line I J of Fig. 1. Fig. 7 is a plan view partly in section taken on line K L of Fig. 1. Fig. 8 is a sectional detail taken on line M N of Fig. 6. Fig. 9 is a detail in perspective.

Similar reference characters refer to similar parts throughout the several views.

The elevator car or cage 1 is of the usual form and raised and lowered in an elevator shaft by cables (not shown) in the usual manner. The particular type of car or cage and the manner of guiding the same in its travel up and down the elevator shaft forming no part of my invention, further description of the same is deemed unnecessary.

Pendant from the underside of the floor of the car, at the end thereof and adjacent to the wall or shaft are the hangers 2—2 and directly opposite at the other end of the car and adjacent the other wall of well is a like pair of hangers 2^a 2^a. Journaled in the lower or free end of these hangers are

the shafts 3 and 3^a. Pinned to these shafts are the combined spur and bevel gears 4—4^a with the spur portions meshing with the racks 5—5^a. These racks run from top to bottom of the elevator shaft or well and are secured to the walls thereof. Meshing with the bevel portions of gears 4—4^a are the bevel gears 6—6^a which in turn are pinned to the shaft 7. Shaft 7 is suitably supported in hangers 8—8^a. The hangers 8—8^a are secured at their upper ends to the underside of the car floor and at their lower ends to the journals 9—9^a which loosely engage the shafts 3—3^a and also form a socket bearing for the ends of the shaft 7. Shaft 7 is further supported by the additional hangers 10—10^a which are also secured to the car floor and in alinement with hangers 8—8^a. Also secured to the floor of the car and located between the hangers 10—10^a and in alinement therewith is a bracket consisting of the downwardly extending arms 11—11 provided with the outwardly extending feet 11^a 11^a, through which it is bolted to the car floor, and terminating in the circular flanged head 11^b. Supported by the cross bars 11^c are the bearings 11^d, and the bearing 11^e is carried by the cross bar 11^f for purposes that will more fully hereinafter appear.

Extending inwardly from the lower end of hanger 10^a toward the vertical center of the device and immediately above shaft 7 is the arm 12. Journaled in the outer end of arm 12 at one end and extending into and supported at the other end by the bearing 11^f in bracket 11 is the governor spindle 13. Pinned to this spindle immediately above the arm 12 is the bevel gear 14 which meshes with the bevel gear 15 which in turn is pinned to shaft 7. Securely pinned to spindle 13 near its upper end is the upper governor head 16. Swingly connected to this head by the arms 17—17 are the governor balls 18—18, which balls are also jointedly connected to the lower governor head 19 by the arms 20—20. Head 19 slidably engages spindle 13. Rods 20^a are rigidly secured to the four corners of head 19, pass loosely through openings in the four corners of head 16 and are secured to the bottom of the circular plate 21. This plate slidably engages the upper end portion of the spindle 13 and is provided with the peripheral flange 22. Thus it is seen that plate 21 will rise and fall on spindle 13 in

response to the raising and lowering of the governor balls by centrifugal force when revolved at high speed.

Loosely suspended on shaft 7 is the large, heavy, highly tempered U shaped steel spring 23. The free ends of this spring are connected by the chains 24-24 to the spindle 25, which spindle is journaled in the bearings 11^a and extends from the upper 10 end of bracket 11 to the upper end of spindle 13 upon which it may rest. The hand wheel 26 is secured to spindle 25 near its upper end. By turning this hand wheel the chains 24-24 will be wound about the spindle and the spring be put under tension by bringing the free ends in toward each other. Secured to the arms of the spring below the chains 24 and in alinement with the head 11^b are the collars 27-27 to which are hinged the 15 hooked arms 28-28. When the spring is put under tension as above described, the hooked ends of these arms engage the upper edge of the flange on head 11^b through openings 11^c and hold the spring in tension after 20 which the hand wheel 26 can be released. Immediately below opening 11^c is the laterally extending lip or apron 11^d acting as a support for the hooked arms 28 when not engaging the flange of head 11^b and acting 25 as a guide to conduct the hooked end of the arm 28 into the opening when the spring is put under tension. It will be observed, as clearly shown in Fig. 8 that the down turned end of arm 28 is in register with the up turned flange 22 of plate 21 and consequently when this plate is raised by the action of the governor balls, it will force the hooks up and off of the edge of the flange on 11^b and permit the spring 23 to immediately expand to its limit. By providing 30 the floor of the car with a trap door, the operator can at any time manipulate the hand wheel 26 and bring the spring back and lock it in tension.

Secured to shaft 7 at each end and adjacent the bevel gears 6-6^a are the friction drums 29-29^a. Adjacent these drums the spur gears 30-30^a are pinned to the shaft. Meshing with these gears are the spur gears 35 31-31^a which are loosely mounted on the counter-shafts 32-32^a. These shafts are journaled respectively in hangers 8-10 and 8^a 10^a. The hubs of the upper gears 31-31^a are extended toward the vertical center of 40 the device and pass loosely through openings in the arms of the spring 23 at the intersection with the counter shafts, and are provided with the collars 31^b and pins 31^c on each side of the spring arms, so that 45 when the spring expands or is drawn into tension the spur gears are moved longitudinally of the shaft with it. The outer end of the hub of these gears is provided with the notches 31^d forming one half of a dental clutch. Adjoining these gears and

pinned to the same shaft are the collars 33-33^a. Hinged thereto are the friction straps 34-34^a which after making practically two full wraps about the friction drums 29-29^a, are loosely secured to the counter shaft 32-32^a. Thus it is seen that the strap is fixedly connected by one end to the shaft and must have a tendency to revolve with the shaft, while the other end is loosely journaled on the shaft and can partake of no shaft movement. The ends of collars 33-33^a adjacent the spur gears 31-31^a are also notched forming the other half of a dental clutch.

When the elevator car ascends or descends 80 the pinions 4 meshing with the stationary racks 5 revolve shaft 7, which through the medium of bevel gears 14-15 revolves the governor balls 18. The weight of these balls and the ratio of the gearing by which they are driven are such that normal speed of travel of the car is not sufficient to cause them to lift through centrifugal force, but when the normal speed is exceeded as would follow from the dropping of the car through 85 breaking of the supporting cables, the governor balls would be thrown out and up with considerable force. In thus raising the flanged lip 22 of plate 21, the lip would contact with the hooked arm 28, release it 90 and permit spring 23 to expand as heretofore explained. This lateral expansion of the spring would slide pinions 31-31^a on shaft 32-32^a and as these pinions are being constantly revolved by their engagement with pinions 30-30^a on shaft 7, a rotating movement would be set up in the collars 33-33^a through the engagement of the notched ends of their hubs, but as these collars cannot revolve beyond the limits of 100 elasticity or slackness in the friction straps 34, the entire weight of the descending car is expended in wrapping the straps about the friction drums 29, thus preventing further rotation of shaft 7 and arresting the 105 descent of the car.

By manipulating hand wheel 26, winding chains 24 about the spindle 25, the arms of spring 23 would be drawn inwardly and cause pinions 31-31^a to slide out of engagement with the collars 33, permitting the car to again start downwardly, for, as previously explained, the pinions 31-31^a which are controlled, in their lateral sliding engagement with the shafts 32-32^a, by the 115 expansion and contraction of the spring 23, would be withdrawn from their clutching engagement with the collars 33-33^a, and as these pinions are free to revolve on the shafts 32-32^a, they could no longer retard the downward movement of the car as they would no longer function in gripping the friction straps 34-34^a about the friction drums 29-29^a, but upon the release of hand wheel 26, which would permit the spring 120 125 130

23 to expand and slide the pinions 31-31^a into clutching engagement with the collars 33-33^a, thereby wrapping the friction straps 34-34^a tightly about the drums 5 29-29^a, descent of the car would be immediately arrested.

What I claim is—

1. An automatic stop for elevator cars consisting of a horizontally extending main shaft supported by said car, stationary racks vertically disposed adjacent to and independent of said car, gearing connecting said racks and shaft, a pair of horizontally disposed counter shafts, friction drums secured to said main shaft, friction straps carried by said counter shafts, and engaging said drums, automatic means controlled by said main shaft whereby the weight of the car becomes effective in causing said straps to grip said drums.

2. An automatic safety device for elevator cars consisting of a horizontal main shaft disposed transversely of and supported by said car; vertically disposed toothed racks adjacent to and independent of said car, gearing connecting said racks and shaft, a pair of horizontally disposed counter shafts, friction drums secured to said main shaft, friction straps carried by said counter-shafts and engaging said friction drums, clutch pinions slidably and revolubly mounted on said counter shafts, clutch collars rigidly secured to said counter shafts and said friction straps, automatic means operated by said main shaft for throwing said clutch members into engagement.

3. An automatic safety device for elevator cars consisting of a horizontally disposed main shaft supported by said car, vertically disposed toothed racks adjacent to and independent of said car, gearing connecting said racks and shaft, a pair of horizontally disposed counter shafts, clutch members mounted on said counter shafts, braking mechanism supported by said counter-shafts and engaging one of said clutch members on each counter-shaft, a U shaped spring carried by said main shaft and engaging the other clutch member on each of the counter

shafts, spring locking means adapted to hold said clutch members out of engagement, automatic spring releasing means controlled by said main shaft for throwing said clutch members into engagement.

4. An automatic safety device for elevator cars, in combination, a horizontally disposed main shaft supported by the car, fixed vertically disposed toothed racks adjacent to and independent of said car, gearing connecting said racks and shaft, a pair of horizontally disposed counter shafts, clutch members mounted on said counter shafts capable of engagement with each other, braking mechanism supported by said counter-shafts and engaging one of said clutch members on each counter-shaft, a spring supported by said main shaft and engaging the other clutch member on each of the counter shafts, manually operated spring locking means adapted to hold said clutch members out of engagement, and an automatic spring releasing means controlled by the velocity of the car for throwing said clutch members into engagement.

5. In an automatic safety device for elevator cars, the combination of a horizontally disposed main shaft supported by said car, vertically disposed toothed racks adjacent to and independent of said car, gearing connecting said shaft and racks, a pair of horizontally disposed counter shafts, clutch-gearing connecting said main shaft and counter shafts, friction drums secured to said main shaft, friction straps capable of engagement with said friction drums and secured to said counter shafts, automatic means externally of the car controlled by the velocity of the car adapted to cause engagement of said clutch gearing to cause said straps to grip said drums, and means manually operated from within the car for releasing said clutch gearing.

Signed by me at Davenport, Iowa, this 19th day of September, 1913.

HENRY BURRMANN.
